UNITED STATES PATENT OFFICE.

SIMEON HAYES, OF PRATTSBURG, NEW YORK.

DESIGN FOR A TRELLIS-FRAME.

Specification forming part of Design No. 1,522, dated February 4, 1862.

To all whom it may concern:

Be it known that I, SIMEON HAYES, of Prattsburg, in the county of Steuben and State of New York, have invented or produced a new and original Design for a Trellis-Frame for Supporting Vines and Plants; and I do hereby declare that the following is a full and exact description of the same, reference being had to the accompanying drawing, making part of this specification.

As represented in the drawing, my design consists of an upright standard *A*, of rather light form and diminishing somewhat as it rises, attached to which is a series of arms *b*, placed at regular intervals apart. They are formed into a regular curve or segment of a circle and attached by the center to the standard, (or they may be made to pass through holes provided in it,) leaving the ends to drop equally on either side. To their ends pendants, in the form of balls, acorns, and conical-beaded drops, as at *c d e f*, are affixed. A variety of these forms on the same trellis has an agreeable effect, disposed as shown in the drawing, the lightest and simplest *c* being placed on the first or smallest arm, and the next somewhat larger, as at *d*, thus increasing consecutively with the arms of the standard. I place the smallest arm at the lowest point and increase the size as they approach nearer the top, giving a similitude to a spreading tree with drooping branches. The re-

semblance may be increased still more by attaching the two uppermost arms *g h* to opposite sides of the standard, they being curved to a smaller circle; but the general feature embodied in my design is the curved or drooping branches, each terminating in a pendant and so arranged as to gradually increase from the lower part of the standard in a regular manner, giving the boundary-lines the general appearance of those of an inverted cone. I surmount the top of the standard with an ornament *k*, of similar character to the pendants, it being composed of transverse beads or curves, or of those combined with planes, or with a ball at the termination, the general form being conical like that of the entire structure and of the pendants. The expanding width of this adapts it to the growth of a class of plants which spread into greater mass and luxuriance of foliage as their growth increases.

I claim as my invention—

The general design and configuration herein described and represented for a plant-supporting trellis.

In witness whereof I have hereunto signed my name in the presence of two subscribing witnesses.

SIMEON HAYES.
